LEVEL WINDER FOR CABLE DRUM (HYDRAULIC)

Edward R. Barrett, Detroit, Mich., assignor to
Gar Wood Industries, Inc., Detroit, Mich., a
corporation of Michigan

Application January 27, 1941, Serial No. 376,042

7 Claims. (Cl. 242—158)

The present invention relates to power winches and particularly relates to improvements in level winders for the cable drums of such winches.

One of the primary objects of the present invention is to provide improved level winders of the type mentioned which are positive in their action in that they are driven in synchronism with the cable drums.

A further object of the invention is to provide improved level winders which are positively driven by a fluid motor which receives its power from a pump mounted on and driven by the winch drive shaft.

Another object of the present invention is to provide an improved winder of the type mentioned in which the speed of the cable guide is regulated so as to compensate for different cable diameters and different drum diameters.

Another object of the invention is to provide adjustable means for regulating the spacing of each cable course, closely to one another, without bunching.

Another object of the invention is to provide improved means of the type mentioned in that it is universal and may be used with cables of different diameters and, also, with drums of different diameters.

Other objects of the invention will become apparent from the following specification, the drawings relating thereto, and from the claims hereinafter set forth.

In the drawings, in which like numerals are used to designate like parts in the several views throughout:

Figure 1 is a side elevational view of a truck having a winch embodying the features of the present invention mounted thereon;

Fig. 2 is an enlarged rear elevational view with parts in cross-section of the winch construction and taken substantially along the line 2—2 of Fig. 1;

Fig. 3 is a diagrammatic view illustrating a modified form of hydraulic circuit for the structure disclosed in Figs. 1 and 2; and

Fig. 4 is a side elevational view of the control and relief valve employed in the circuit of Fig. 3.

Referring to the drawings, and referring particularly to Figures 1 and 2 thereof, an automotive truck is generally indicated at 10 having a power which generally indicated at 12 mounted thereon. Such power winch in general is of conventional construction and includes a standard 14 having upstanding mounting brackets 16 thereon. A drive shaft 18 is mounted upon suitable bearings within the brackets 16. A speed reducer drive mechanism 20 is also mounted upon the standard 14 and is operatively connected to the drive shaft in the usual way. Such speed reducer mechanism receives its power from a

train of gears 22 which may be operatively connected to a power take-off of the automotive engine through a drive shaft indicated at 24. Control means in the form of a lever 26 may be mounted within the cab for controlling the power take-off so that the speed reducer means 20 may be driven as desired to rotate the drive shaft 18.

It will be readily appreciated that while the winch is here illustrated as being mounted on a vehicle chassis, the present invention is not limited thereto; but the winch could be mounted on a separate standard having its own power plant, or could be otherwise driven.

A winding drum in the form of a spool 28 is keyed to shaft 18 for rotation therewith and another spool 30 may also be keyed to one end of the shaft 18 for rotation therewith if desired. A cable 32 is connected to the drum 28 and is wound thereon upon rotation of drive shaft 18 in the usual way. The structure so far described is of conventional nature.

According to the present invention, a level winder is provided for guiding the cable 32 as it is wound upon the drum so that such cable will be evenly distributed along the length of the drum and in superimposed even convolutions. Such level winding means includes an upstanding arm 34 having a movable guide eye 36 for receiving the cable 32 therethrough. Such guide eye 36 is formed with an integral depending stem or rod 37 which is slidably received through aligned openings in lugs 39 formed on the arm 34. The rod 37 has an enlarged lower end 41, and a spiral compression spring 43 embraces the lower end of the rod with its ends abutting against the enlargement 41 and the lower lug 39. The eye 36 is thus rigid against lateral movement but is resiliently movable outwardly. The arm 34 is fixedly secured to a transversely extending rack 40 which is slidably mounted within bearings 42 mounted on the standard 14. The rack 40 is reciprocated and as it is reciprocated it will be evident that the cable 32 is guided on to the drum as the arm 34 reciprocates longitudinally of the drum between the ends thereof.

The rack 40 meshes with a pinion 44 which is fixedly connected to a drive shaft 46 of a fluid motor 48. The fluid motor 48 may be one of any number of standard fluid motors now on the market, but is illustrated as being of the gear type having meshing gears 50 and 52 mounted within the housing of the motor. The gear 50 is keyed to the drive shaft 46 for driving the pinion 44 and the gear 52 is mounted upon an idler shaft 55 in the usual way. Inlet and outlet ports are provided through the housing in the usual way; and in the present instance the motor is reversible so that each of such ports alternately forms an inlet and outlet port for hydraulic fluid supplied the motor.

In order to drive the fluid motor 48, to reciprocate the arm 34, an hydraulic pump 54, which may be one of a number of standard pumps now on the market but is here illustrated as of the gear type, is provided. Such pump includes the usual pair of intermeshing gears 56, one of which is keyed to a drive shaft 58 for driving the pump. The drive shaft 58 is directly connected to the winch drive shaft 18 so that upon rotation of such shaft the pump 54 is driven.

The hydraulic circuit for supplying the fluid to the pump 54 for driving fluid motor 48 is reversible and includes a supply tank or reservoir 60 having a conduit 62 leading into the inlet 60 having a conduit 62 leading into the inlet 60 of pump 54. An outlet conduit 64 leads from the discharge or high pressure side of the pump 54 and communicates with a four-way reversing valve 66 through a central port 68. The reversing valve 66 has a spool 70 slidably disposed therein which is formed with outwardly and upwardly projecting end portions 72. Such portions 72 provide the means for shifting the valve to reverse the flow of fluid through the circuit when such end portions are engaged by stops 74. Such stops 74 are connected to or formed integral with the rack 40 so that as the rack reaches the end of its travel in either direction, it shifts the valve to reverse the flow of fluid through the hydraulic circuit.

The valve 66 is provided with ports 76, 78, 80, and 82 therethrough. Ports 76 and 80 have conduits 84 and 86, respectively, communicating therewith, and both of such conduits communicate with a return conduit 88 which returns to and communicates with tank 60. Ports 78 and 82 have conduits 90 and 92, respectively, communicating therewith, and the opposite ends of such conduits communicate with the ports leading into the fluid motor 48. As stated above, such last mentioned ports each alternately provide the inlet and outlet ports for the fluid motor 48.

With the parts in the positions shown and with the drive shaft 18 operating to drive drum 28, the pump 54 is driven therewith. Fluid under pressure is delivered to the distributing and reversing valve 66 through ports 68 and enters conduit 92 through port 82, to drive the fluid motor 48 in one direction to move the rack 40 and arm 34 in the direction indicated by the arrows in Fig. 2. The fluid from the motor 48 returns through conduit 90 into valve 66 through port 78, out of valve 66 through port 80, into conduit 86 and returns to the tank through conduit 88. At this time, the port 76 is covered as shown.

When the rack 40 reaches the end of its travel toward the left, as indicated in Fig. 2, one of the stops 74 strikes one of the arms 72 to shift the spool 70 by moving it toward the left. The fluid under pressure then enters through port 68 and passes out of the valve through port 78 into conduit 90 to drive the fluid motor in the opposite direction and to move the rack and arm in the opposite direction, that is, toward the right viewing Fig. 2. The fluid from the motor 48 is conducted through conduit 92 into valve 66 through port 82 and leaves the valve 66 through port 76 into conduit 84 and returns to the tank through conduit 88. With the valve in this position, the port 80 is closed by the spool.

It will thus be seen that as the drum 28 is rotated, the arm 34 is synchronously moved therewith since the pump 54 is driven from shaft 18. The speed of the arm is automatically set

with the speed of the drum since the speed of the drum and the speed of the pump 54 are directly proportionate to each other.

Referring to Figures 3 and 4, a modified hydraulic circuit is illustrated in which the speed of travel of the rack 40 may be adjustably varied in order to compensate for different cable diameters and/or different drum diameters. The spacing of each of the cable courses may be closely regulated without any danger of bunching the adjacent convolutions over each other. With this circuit, a standard drive means for the level winder may be provided which may be universally applied to winches having drums of different diameters or having cables of different diameters. Corresponding parts of the structure described above in connection with Figures 1 and 2 have been given corresponding numerals in the embodiment illustrated in Figures 3 and 4. Referring to these figures, the oil is drawn from the reservoir 60 through a supply conduit 62 by reason of the actuation of pump 54. Liquid under pressure is then conducted through conduit 64 into a chamber 94 over the combined flow control and relief valve, generally indicated at 96. Such valve 96 is of a standard construction and forms no part of the present invention per se, except in the combination claimed.

Control of the flow of fluid from the chamber 94 to the member to be actuated, which, in the present instance, is the pump 48, is by means of an orifice throttle valve 98, which is constructed with a passageway 99 of variable cross-sectional area.

In order to maintain a constant flow through the orifice valve 98 so that the flow rate from the chamber 94 to conduit 101 will be constant, a piston 102 is provided, the lower part of which defines an upper wall of the chamber 94 and the upper part of which defines the lower wall of chamber 104. A small relief or guide chamber 106 is formed in the casing above the piston 102, and an exhaust valve is provided at the lower end of the piston comprising a valve set 108 and a tapered valve member 110. The center of the piston 102 is preferably hollow. The area of the valve 110 below the piston 102 is substantially balanced by a guide 112 which projects into the chamber 106. The effective size of the orifice valve 98, and hence the volume of liquid passing therethrough, is controlled by means of an adjustable lever 114 which is fixed to the valve 98 for adjustably controlling the position thereof.

Direct application of the liquid under pressure from the combined flow control and relief valve is by means of the four-way valve 66, having the piston and ports arranged as in the embodiment described above.

A relatively restricted conduit 116 connects the operating pressure in the conduit 101 with the chamber 104 above the piston 102. Relative pressures on either side of the piston 102 determine the flow of liquid under pressure entirely through the orifice valve 98, or partly or substantially entirely through the outlet valve 108. A pressure relief valve or ball 118, backed by a spring 120 of predetermined strength, variable by adjusting means 122, controls the flow of fluid through the passageway 124. An auxiliary exhaust conduit 126 connects the chamber surrounding the spring 120 with the exhaust conduit 128.

The movement of the elements of pump 48 may be maintained at a constant rate of speed corre-

sponding to a given setting for the orifice valve 98, or such speed may be adjustably varied by movement of the handle 114. Rapid return, if desired, or partial rapid return or rapid approach may be accomplished by temporarily by-passing the liquid under pressure around the speed control and relief valve and through by-pass shut-off valve 130.

It will, therefore, be seen that for a constant delivery by pump 54, the speed of movement of the rack 40 may be adjustably varied by varying the position of the valve element 98. In this way, this construction may be readily adapted to take care of the desired speeds with cables and/or drums of different diameters.

Also, while in the embodiment specifically illustrated the guide arm 34 is reciprocated by the rack and pinion construction, it is to be understood that such arm may be otherwise hydraulically reciprocated, such as by a reciprocating piston connection which could be substituted for the fluid motor 48 and the rack and pinion.

Formal changes may be made in the embodiment of the invention illustrated and described without departing from the spirit and substance of the invention, the scope of which is commensurate with the appended claims.

What is claimed is:

1. A power winch construction comprising, in combination, a drum having a cable wound therearound, driving means for rotating said drum and including a drive shaft, a reciprocable guide arm having a cable receiving guide portion and movable longitudinally of said drum between the ends thereof, and power means for reciprocating said arm, said power means including a reciprocating rack connected to said arm, a pinion in mesh with said rack, a reversible fluid motor operatively connected to said pinion to drive the same, and means to reversibly drive said fluid motor in synchronism with rotation of said drum to cause said arm to reciprocate therealong.

2. A power winch construction comprising, in combination, a drum having a cable wound therearound, driving means for rotating said drum and including a drive shaft, a reciprocable guide arm having a cable receiving guide portion and movable longitudinally of said drum between the ends thereof, and power means for reciprocating said arm, said power means including a reciprocating rack connected to said arm, a pinion in mesh with said rack, a reversible fluid motor operatively connected to said pinion to drive the same, and means operatively connected to said drive shaft to reversibly drive said fluid motor in synchronism with rotation of said drum to cause said arm to reciprocate therealong.

3. A power winch construction comprising, in combination, a drum having a cable wound therearound, driving means for rotating said drum and including a drive shaft, a reciprocable guide arm having a cable receiving guide portion and movable longitudinally of said drum between the ends thereof, and power means for reciprocating said arm, said power means including a reciprocating rack connected to said arm, a pinion in mesh with said rack, a reversible fluid motor operatively connected to said pinion to drive the same, and hydraulic means operatively connected to said drive shaft to reversibly drive said fluid motor in synchronism with rotation of said drum to cause said arm to reciprocate therealong.

4. A power winch construction, comprising, in combination, a drum having a cable wound

therearound, driving means for rotating said drum and including a drive shaft, a reciprocable guide arm having a cable receiving guide portion and movable longitudinally of said drum between the ends thereof, and power means for reciprocating said arm, said power means including a reciprocating rack connected to said arm, a pinion in mesh with said rack, a reversible fluid motor operatively connected to said pinion to drive the same, a pump operatively connected to said drive shaft and driven thereby, and means providing a reversible hydraulic circuit between said pump and motor to reversibly drive said motor in synchronism with rotation of said drum to cause said arm to reciprocate therealong.

5. A power winch construction, comprising, in combination, a drum having a cable wound therearound, driving means for rotating said drum and including a drive shaft, a reciprocable guide arm having a cable receiving guide portion and movable longitudinally of said drum between the ends thereof, and power means for reciprocating said arm, said power means including a reciprocating rack connected to said arm, a pinion in mesh with said rack, a reversible fluid motor operatively connected to said pinion to drive the same, a pump operatively connected to said drive shaft and driven thereby, means including a reversing valve providing a reversible hydraulic circuit between said pump and motor to reversibly drive said motor, and means operatively connecting said valve with said rack to reverse said valve upon reciprocation of said rack.

6. A power winch construction comprising, in combination, a drum having a cable wound therearound, driving means for rotating said drum and including a drive shaft, a reciprocable guide arm having a cable receiving guide portion and movable longitudinally of said drum between the ends thereof, and power means for reciprocating said arm, said power means including a reciprocating element connected to said arm, a pump operatively connected to said drive shaft and driven thereby, hydraulic means including a reversible valve providing a reversible hydraulic circuit between said pump and element to reversibly drive said element, and means interposed in said circuit to control the volume of fluid flowing therethrough while said pump may have a constant discharge, and means operatively connecting said valve with said reciprocating element to reverse said valve upon reciprocation of said element.

7. A power winch construction comprising, in combination, a drum having a cable wound therearound, driving means for rotating said drum and including a drive shaft, a reciprocable guide arm having a cable receiving guide portion and movable longitudinally of said drum between the ends thereof, and power means for reciprocating said arm, said power means including a reciprocating element connected to said arm, a pump operatively connected to said drive shaft and driven thereby, adjustable hydraulic means including a reversible valve providing a reversible hydraulic circuit between said pump and element to reversibly drive said element, and means interposed in said circuit to control the volume of fluid flowing therethrough while said pump may have a constant discharge, and means operatively connecting said valve with said reciprocating element to reverse said valve upon reciprocation of said element.
